UNITED STATES PATENT OFFICE

GEORGE D. OVERHOLTZ, OF FAIR OAKS, PENNSYLVANIA, ASSIGNOR TO McCLINTIC-MARSHALL CORPORATION, OF BETHLEHEM, PENNSYLVANIA, A CORPORATION OF PENNSYLVANIA

OUTDOOR ADVERTISING STRUCTURE

Application filed March 28, 1931. Serial No. 526,092.

This invention relates to improvements in outdoor advertising structures of the character embodying a supporting framework, a panel construction secured thereto, molding or trim including decorative base members, and a lattice structure disposed below the panel construction and extending between said base members. My invention is particularly related to new and improved means for detachably securing the lattice to the structure.

The lattice employed in the modern all-metal outdoor advertising structure is preferably formed of sheet metal. Like all other parts of such structures, the lattice must necessarily be of such construction and be mounted in such a manner that it may be readily erected and taken down.

Among the objects of my invention are to provide simple and efficient means for detachably securing the lattice to the structure; to provide a plurality of lattice sections having reinforcing means thereon; to provide attaching means co-acting with means on the lattice to removably secure the lattice to the structure; and to provide clamping means to secure the lattice to the base members of the advertising structure.

Additional objects and advantages will become apparent from the following description taken in connection with the accompanying drawings, wherein:

Fig. 1 is a front elevational view of an outdoor advertising structure embodying my invention;

Fig. 2, a front perspective view of two lattice sections showing the attaching means;

Fig. 3, an enlarged detail view of one of the attaching means;

Fig. 4, a sectional view taken on the line IV-IV of Fig. 3;

Fig. 5, a rear perspective view of an end lattice section, showing the means for clamping the same to a corner base member of the structure; and

Fig. 6, a cross-section taken on the line VI-VI of Fig. 5.

Referring to the drawings, the type of advertising structure illustrated is what is known in the art as a bulletin, and includes a supporting framework having spaced-apart

angle-iron uprights 2, a panel construction consisting of a plurality of removably mounted panel sections 3 secured to the framework in any suitable manner, and metal molding or trim bordering the panel sections, including a cornice 4, columns 5, bottom molding 6, corner bases 7, and intermediate sub-bases 8.

Positioned below the bottom molding 6 and extending between the corner bases 7 and the sub-bases 8, I provide a metal lattice of diamond or diagonal form, comprising a plurality of lattice sections extending between the uprights 2 and including end sections 9 and intermediate sections 10.

The said lattice sections are preferably formed of sheet metal cut and bent into the desired configuration, and include a plurality of spaced-apart inclined channel-like portions 11. Spaced-apart diamond-shaped openings 12 are formed in the sheet between the channel-like portions 11, by cutting and stamping out portions of the metal and bending the same rearwardly of the channel-like portions to form a series of fins 13, disposed at a like and opposite inclination to the said channel-like portions.

One of the important features of my invention resides in the reinforcing framing members for the lattice sections, arranged and constructed to provide adequate means for securing the sections together, and to cooperate with attaching means for securing the lattice to the structure. Thus, reinforcing members 14, preferably formed of sheet metal and channel-shaped in cross section, are secured along the top edges of the lattice sections by spot welding the front flanges 15 thereof to the upper portions of the lattice channel-like portions 11. The flat web portions 16 of said members extend rearwardly of the lattice sections and terminate in down-turned longitudinal flanges 17.

Similarly, the lower edges of the lattice sections are provided with reinforcing members 18 of Z-shape in cross-section, having upturned flanges 19 thereof spot welded to the channel-like portions 11. The flat web portions 20 extend rearwardly of the sections and terminate in down-turned longitudinal flanges 21, said flanges 21 being pref-

erably disposed in the same vertical plane as the flanges 17 of the upper reinforcing members.

The end portions of the reinforcing members 14 and 18 extend beyond the ends of the lattice sections, and are formed with offset portions for joining said members together.

Thus, in Fig. 2, I have illustrated the joining ends of two lattice sections, constructed in the manner of my invention, it being understood that the other ends of said sections will be formed in a like manner. The adjacent end portions of the lattice are adapted to be overlapped and joined along the lines 15 *z-z* by means of suitable screws or bolts passed through the registering openings 22 in the channel-like portions 11. Likewise, the flat web portions 16 and 20 of the reinforcing members are designed to be overlapped and joined by means of screws and the registering openings 23.

To permit the projecting end portions of the reinforcing members to be overlapped in this manner, and to facilitate assembly 25 thereof, the front flanges 15 and 19 on one lattice section are cut away as at 24, and the rear down-turned flanges 17 and 21 are cut away a like distance on the adjoining lattice section, as at 25. With the adjacent ends 30 of the reinforcing members formed in this manner, they may be readily engaged without overlapping of the flanges above stated, thereby dispensing with any difficulty resulting from trying to telescope the said 35 members one into the other.

For the purpose of securing the lattice to the structure, the angle iron uprights 2 are provided with U-shaped or locked clips 26 for receiving the lower down-turned flanges 40 21 of a lattice section. In assembling the lattice on the structure, an end of the said flange 21 of a lattice section is positioned in a clip 26 in the manner of Fig. 2, and the lattice swung toward the upright 2 for engagement of the flange 17 with retainer means including a retainer 27 preferably formed of a flat rectangular plate of metal having a central bolt-receiving opening 45 therein for positioning the same on a bolt 50 28 on the upright.

The width of the member 27 is such that when it is in the horizontal position of Fig. 4, the flange 17 of the lattice section will pass thereover. When said flange has been moved 55 thereover into engagement with the front face of the upright 2, the retainer may be rotated on the bolt to assume the vertical position of Figs. 2 and 3, and upon tightening the bolt, the retainer will securely clamp the 60 said flange to the upright.

As stated herein, the lattice sections extend between the uprights 2, and hence one of two adjoining sections may be secured to an upright in the manner of Fig. 2, and the other 65 adjoining section bolted thereto by means of

the registering openings 22 and 23. A decorative apron or trim 29 may be provided along the lower edges of the lattice sections, being secured thereto by welding and having offset end portions of the form of Fig. 2, to provide a continuous apron when the lattice sections are assembled.

A further feature of my invention resides in additional means for securing the assembled lattice to the structure, particularly the end sections of the lattice. An end lattice section 9 is shown in Fig. 5, preferably extending behind the corner base member 7. The extreme end of said lattice section is provided with a vertical angle member 30 welded thereto to provide additional reinforcement, thereby preventing injury to the free end portions of said lattice.

The corner base 7 is angular in form, and is preferably formed of sheet metal, having a rectangular depression or panel 31 in the front wall or face 32 thereof. The inner vertical edge of said base is bent to form an angle portion 33 having a rear vertical flange 34.

Secured to the rear of the front wall 32 by means of a spot welding, I provide a vertically extending Z-shaped member 35 having a vertical flange 36 disposed in the same plane and spaced from the flange 34, to form a vertical slot 37 open at the ends thereof. Said slot 37 is designed to receive bolts 38 therein for mounting U-shaped clamping members 39. The clamping members 39 are provided with extending leg portions 40 and a plurality of bolt receiving openings 41.

For the purpose of positioning the clamping members 39, the bolts 38 are inserted in the slot 37 and the shanks of the bolts extended through any of the adjacent diamond-shaped openings 12 in the lattice. By reason of the plurality of openings 41 in the members 39, the clamping members are adjustable to span the distance between a channel-like portion 11 of the lattice and the rear of the panel 31 of the base 7, and when so positioned, the leg portions 40 of said members engage and contact with said portions 11 and panel 31. Upon tightening the nuts on the bolts 38, the clamping members will clamp the lattice securely against the rear of the panel 31, as particularly shown in Fig. 6.

Thus, it will be seen that by means of my invention, the entire assembled lattice, comprising a plurality of sections, may be securely mounted on an outdoor advertising structure. The attaching or securing means of my invention may be readily applied or removed to provide for ready attachment and detachment.

The sub-bases 8 may be formed with the slot construction of the corner bases 7, whereby they may be readily applied to the front of the lattice structure by means of the bolts 38 and the clamps 39.

I claim:

1. In an outdoor advertising structure, the combination with an upright member of a support framing, of a sheet metal lattice member including a channel-like reinforcing frame member overlapping and secured to the upper edge of the lattice and a substantially Z-shaped reinforcing member overlapping and secured to the lower edge, and spaced-apart lower and upper retaining means on the upright for cooperation with a flange of the respective lower and upper reinforcing members of the lattice. 70
2. In an outdoor advertising structure, the combination with an upright member of a support framing, of a sheet metal lattice member including a channel-like reinforcing frame member overlapping and secured to the upper edge of the lattice and a substantially Z-shaped reinforcing member overlapping and secured to the lower edge, and spaced-apart lower and upper retaining means on the upright for cooperation with a depending flange of the respective lower and upper reinforcing members of the lattice, said lower retaining means including a hook-shaped member for engagement with the flange of the lower reinforcing member and said upper retaining means comprising a bolt and nut construction and an adjustably mounted member. 80
3. In an outdoor advertising structure, the combination with an upright member of a support framing, of a sectional sheet metal lattice associated therewith, each section including a channel-like reinforcing frame member overlapping and secured to the upper edge of the lattice and a substantially Z-shaped reinforcing member overlapping and secured to the lower edge, and spaced-apart lower and upper retaining means on the upright for cooperation with an aligned flange of the respective lower and upper reinforcing members of a lattice section, said upper and lower reinforcing members extending beyond the edges of adjacent lattice sections and formed with offset portions for joining said members together in overlapped relationship. 90
4. In an outdoor advertising structure, the combination of a support framing, a corner base member, an end lattice section having an end thereof associated with the corner base member, means on the corner base forming a bolt receiving slot, and a clamping member for clamping the said end of the lattice section to the corner base, said member comprising a clamp having its body portion in spaced relation to the lattice and having legs engaging the base member and the lattice and a bolt passing through the body portion of said clamp and lattice and entered in the aforementioned bolt receiving slot. 100
5. In an outdoor advertising structure, the combination of a support framing, a sheet metal corner base member, a sheet metal end lattice section associated with the corner base member, slot forming means on the base member including a bent edge and a member secured to the base member, and means for securing an end portion of the lattice section to the base member including a clamp member, a bolt on which the clamp member is loosely mounted, said bolt passed through the clamp member and the lattice and having an end entered in the slot. 105
- In testimony whereof I affix my signature.
